UNITED STATES PATENT OFFICE.

NELSON J. RUSSELL, OF CHICAGO, ILLINOIS.

FUEL-SAVING DEVICE.

Application filed March 19, 1925. Serial No. 16,590.

To all whom it may concern:

Be it known that I, NELSON J. RUSSELL, a citizen of the United States, and a resident of the city of Chicago, county of Cook, and State of Illinois, have invented certain new and useful Improvements in Fuel-Saving Devices, of which the following is a specification.

My invention relates to a fuel saving device, and particularly to a device of this kind which is arranged for mounting in the fire pot of a furnace or boiler for conducting air from the grate through the burning fuel and to the top of said fuel, thus providing for the complete combustion of gases at the top of the fuel in the fire pot; and the main object of the invention is to provide an air conveying member with insulating means therearound and with a protecting casing placed around said insulating means to fully protect the same, and thereby to protect said conveying means, thus prolonging the life of the insulating means as well as of the air conveying means.

Other objects will appear hereinafter.

The invention consists in the combinations and arrangements of parts hereinafter described and claimed.

The invention will be best understood by reference to the accompanying drawings forming a part of this specification, and in which,

Fig. 1 is an elevational view of a boiler, partly broken away, showing my invention mounted in position therein;

Fig. 2 is an enlarged horizontal cross-sectional view of the invention, taken on line 2—2 of Fig. 1;

Fig. 3 is an enlarged vertical sectional view of the invention, taken on line 3—3 of Fig. 1;

Fig. 4 is a slightly reduced plan view of the invention illustrated in Fig. 3, with a part of the cover broken away; and

Fig. 5 is a cross-sectional view, taken on the line 5—5 of Fig. 3, being slightly reduced.

In the drawings I have shown my invention mounted on a grate 10 and in the fire pot 11 of a boiler 12, its upper end extending sufficiently high in the fire pot to be above the top or head of the fuel 13 therein.

The form of invention as illustrated preferably comprises a conduit 14 provided with a base portion 15 arranged to be

mounted and supported on the grate 10, and being opened at the lower end for receiving air through said grate, and vertical strengthening plates 15' are extended inwardly from said base as shown. Baffle means are provided on the interior of the conduit for conducting or transferring the heat from the walls of the conduit toward the interior thereof so as to thoroughly and effectively heat the air passing up through the conduit and are also arranged to be effective in deflecting the ascending heated air current through said conduit. These baffle means preferably include cross plates or diaphragms 16 extending across the conduit, and substantially vertical plates 17 extending inwardly from the walls of the conduit to points near the center line thereof, as best shown in Figs. 2 and 3, thus leaving a central space 18 between said vertical plates for the free upward passage of air, and the cross plates 16 are alternately provided the one with a central opening 19, and the succeeding one with a plurality of non-central openings 20 and placed in staggered relation to the central openings 19 in the adjacent plates, as shown in Fig. 3. This arrangement of the various baffle elements thus causes the heat to be radiated and conducted inward from the walls of the conduit 14 and to be thoroughly transferred to the air which is deflected by said baffle means in its passage through the conduit, and this arrangement, by transferring the heat from the conduit inwardly, is thus effective in prolonging the life of the conduit by preventing burning up thereof.

A cover 21 is provided and has an inwardly extending flange 22 which engages within the wall of the conduit 14, and this cover is preferably firmly fastened on the conduit as by means of bolts 23 having nuts 24 on the outer side to be readily removed for withdrawing the bolts and allowing convenient removal of the cover and replacing thereof if the same is burnt up or otherwise damaged. Openings or perforations 25 are provided around the side or the cylindrical part of the cover for directing the air laterally into the gases above the fuel 13. A projection or thickened portion 26 is provided on the inner side of the top of the cover and is pointed or bevelled downwardly, directly over and adjacent to the central opening 19 in the upper cross plate 110

16, and is effective in additionally heating the air rising through the conduit and in deflecting it outwardly through the openings 25. This portion is preferably made 5 solid so as to prevent burning down, as the air is extremely hot when it reaches this portion 26, which acts as a hot-spot and additionally heats the air deflected thereby and acts as a neutralizer for keeping the 10 air neutrally hot as it passes out of the openings 25. As this air rises through the conduit it is heated and expanded to an increasing degree and thus rushes forcefully out of said openings 25 to thoroughly 15 mingle with the gases which form at the top of the fuel 13.

As the heat in the fire pot is extreme, it is apparent that the walls of the conduit are 20 apt to be burnt through, I therefore provide 20 protecting means around the walls of the conduit so as to shield the same from a considerable portion of the excessive heat and thus to prolong the life thereof. This protecting means or shielding means preferably 25 consists of a casing or container 27 which is mounted around the walls of the conduit and spaced therefrom to provide a space 28 between it and said conduit for the circulation 30 of air, and openings 29 are preferably also 30 provided adjacent the bottom of the conduit so that the air coming through the grate may pass into this space 28 and upwardly therethrough, to pass outwardly 35 through the upper annular opening 30 provided between the upper end of said casing and the cover 21 and the conduit 14, said 40 heated air also mingling with the gases issuing from the burning fuel. Said casing 27 is supported on the base 15 and is preferably 45 fastened to the container, as by means of bolts 31 and spacing sleeves 32 and nuts 33 which are placed on the inside of the conduit to prevent burning up thereof and to 50 permit loosening and removing the same 45 through the grate when opened. The protecting and shielding means preferably also includes a non-conductor of heat or heat insulating means 34, placed in the space 28 around the conduit, and this insulating 55 means may be in the form of one or more sheets of asbestos or may be of any suitable insulating means desired, and preferably being so arranged that an air space is also provided between the casing and conduit to 60 permit the air ascending from the bottom opening 29 through the upper opening 30, thus continually cooling the air and any other non-conducting means existing in said space 28 and preventing the conduit from 65 being overheated or burnt up. This casing is constructed of a material or metal which will resist heat to a considerably greater degree than the conduit, and is preferably made of metal such as wrought iron or 70 wrought steel, which has a considerably 75

higher point of fusion and of softening than has the conduit, which is preferably constructed of cast iron.

It is apparent from the above disclosure that with a protecting means as set forth above, the main construction or air conveying or heating means, is entirely protected and prevented from being burnt up, and it is apparent that the casing 27 protects not only the conduit with its contained 70 elements, but more particularly protects the heat insulating means 34 or the means which is usually employed for protecting the main mechanism or air conveying means and which in other constructions, without the use of such casing, is readily cracked or 75 broken up and destroyed; and it is furthermore apparent that this casing 27 may be readily removed when damaged by heat and may be replaced by a new one, by raising 80 it upwardly along said conduit and cover, and likewise that the cover 21 may be removed and replaced, all while the main construction, which is more expensive, 85 is entirely protected and can be retained. 90 If ashes or soot finds its way into the space 28, this is invariably porous, permitting the air to ascend therethrough, and will thus only act as an additional insulation, and the insulating means 34 can be used in the form 95 of a thick or a thin member, thus the insulating means of proper resistance may be used, or may be entirely omitted, so as to permit the exact amount of heat from the burning fuel in the fire pot to be transferred 100 through the casing 27 to the conduit, to be transferred from its wall through the baffle elements 16 and 17 to the air ascending 105 through the device and pass through the top of the burning fuel to mingle with the fuel gases. This insulating means 34 may be readily removed by drawing it upwardly 110 along the conduit and cover, similar to removing the casing 27.

While I have illustrated and described the 110 preferred form of construction for carrying my invention into effect, this is capable of variation and modification without departing from the spirit of the invention. I, therefore, do not wish to be limited to the 115 precise details of construction set forth, but desire to avail myself of such variations and modifications as come within the scope of the appended claims.

Having described my invention what I 120 claim as new and desire to secure by Letters Patent is:

1. A fuel saving device for a furnace, comprising means for mounting the device on the furnace grate and including a conduit 125 and a casing of greater heat resisting material than said conduit mounted about said conduit and providing a space therearound adapted to receive a nonconductor of heat, said conduit having openings adjacent its 130

lower end for admitting air to said space, and said casing providing an outlet opening at its top and acting as a protection for said conduit and said nonconductor.

5. 2. A device of the class described comprising a conduit with base means for removably mounting the device on a furnace grate and being open at the bottom for receiving air through said grate, a casing 10 mounted around said conduit to rest on said base means and being spaced from said conduit and readily removable therefrom, said conduit having openings to admit air from said base means to said space, and insulating means mounted within said space.

15. 3. A device of the class described comprising a cylindrical conduit having baffle elements therein which are formed integral with the conduit, said elements including a 20 plurality of diaphragms provided with openings which are staggered in the alternating diaphragms and a plurality of integral vertical plates extending inwardly from the conduit between each pair of diaphragms.

25. 4. A conduit provided with baffle elements for deflecting the air passing therethrough, and for transferring the heat from the walls of the conduit to the interior thereof, the upper one of said baffle elements having a 30 central opening, a cover mounted on said conduit and having an integral conical deflecting member beneath the top thereof with a central depending point positioned above a central opening in the upper one of said 35 baffle elements.

40. 5. A device of the class described comprising a conduit having diaphragms with openings therein, and having cross plates alternating with said diaphragm, and a cover removably mounted on said conduit and hav-

ing a central deflecting element mounted on its inner side with the lower point of said element extending adjacent to and over a central opening in the upper diaphragm, there being side openings in the walls of said 45 cover for the lateral exit of the deflected air.

6. A device of the class described comprising a conduit with base means removably mounted on a grate and being open at the bottom for receiving air through said grate, 50 a cover removably mounted on the top of said conduit, a casing mounted around said conduit to rest on said base means and being spaced from said conduit and being readily removable from said conduit and said cover, 55 and insulating means mounted in said space and being of greater cross section than said cover and therefore readily removable and replaceable without disturbing said casing or said cover.

60. 7. A device of the class described comprising a conduit with integral base means having strengthening flanges therein, integral elements in said conduit for transferring heat from the walls of the conduit to the interior thereof, said means including diaphragms with perforations and plates extending inwardly from said conduit which alternate with said diaphragms, a cover 65 removably mounted on said conduit and having an integral member with a downwardly projecting point for deflecting air through openings provided in said cover, insulating means removably mounted around said conduit and a casing removably mounted around 70 said insulating means to protect the same.

75. In testimony whereof I have signed my name to this specification.

NELSON J. RUSSELL.
